UNITED STATES PATENT OFFICE.

MABEL C. L. DEEKS, OF TORONTO, ONTARIO, CANADA.

SANITARY GUARD FOR BOTTLES.

1,182,993.

Specification of Letters Patent. Patented May 16, 1916.

Application filed April 9, 1915. Serial No. 20,206.

To all whom it may concern:

Be it known that I, MABEL CAROLINE LOUISE DEEKS, a subject of the King of Great Britain, and resident of the city of 5 Toronto, county of York, Province of Ontario, in the Dominion of Canada, have invented certain new and useful Improvements in Sanitary Guards for Bottles, as described in the following specification and 10 illustrated in the accompanying drawings, that form part of the same.

The objects of the invention are, to obviate the disagreeable and unsanitary features incident to the dripping of the contents 15 of medicinal and similar bottles, and to avoid the marring of furniture and covers.

A further object is to effect the preservation of labels on bottles for reference. 20 The principal feature of the invention consists in the novel construction of an absorbent elastic band adapted to be placed around the neck of a bottle, whereby any dripping of the contents of the bottle down 25 the side of the neck is arrested and absorbed and effectively prevented from flowing farther down the bottle.

In the drawings, Figure 1 is a perspective view of a portion of a bottle showing my invention applied thereto. Fig. 2 is an elevational view showing my absorbent band in section. Fig. 3 is an enlarged cross sectional detail of the band.

Like numerals of reference indicate corresponding parts in each figure.

In the practical application of this invention, I find that in order that the band may be effective in preventing the flow from the drip of the bottle down the sides while 40 the bottle is in use, that is, until all of the contents are used up, it is necessary that the band shall be of such a nature as to absorb the liquid and not allow the outer surface to become coated or glazed so that the 45 fluid will eventually find its way over the top of the band.

I am aware that several forms of bands purporting to accomplish the result which I have achieved have been proposed but 50 none of these have come into actual use evidently through their failure to attain the result intended.

The band herein shown consists of a band 1 of a soft absorbent textile fabric,

such as stockinet which is preferably formed 55 with the weave bias of the band and having the edges 2 thereof curled inwardly to engage the neck 3 of the bottle. The curling inward of the edges of the band is effected in a very simple manner by forming 60 the band considerably smaller than the diameter of the neck of the bottle, and upon the stretching of same the edges curl inward. I preferably arrange a filler 4 of a soft absorbent material such as absorbent 65 cotton between the inwardly curled edges of the band so as to provide the maximum of absorption.

In the use of this invention the woven or knitted fabric to be used is cut to the desired widths and may be made of any tubular form the desired circumference or from flat strips having the ends secured together in any suitable manner.

A band constructed as described has very 75 high absorption qualities and will take in even very sticky fluids to a very great extent without the pores becoming clogged and the material in drying forming a hard surface over which the succeeding flow will 80 find a path.

The effective stopping of the drip from the head of a bottle flowing down the side thereof keeps the sides of the bottle always 85 clean, prevents the marring or destruction of the label and also avoids the collection of dirt or germs which may be again transmitted by a person picking up the bottle. Other advantages will be obvious.

What I claim as my invention is:— 90

1. A sanitary guard for bottles, comprising an endless band of absorbent textile material adapted to embrace the neck of the bottle, and being formed of a tubular length of material having the edges rolled inwardly. 95

2. A sanitary guard for bottles, comprising, an elastic band of textile material having inturned edges and a band of soft absorbent material arranged within the band of textile material. 100

Signed at the city of Toronto, county of York, Province of Ontario, in the Dominion of Canada, this 29th day of March 1915.

MABEL C. L. DEEKS.
